UNITED STATES PATENT OFFICE.

JOSEPH KNOWLES, OF EDMONDS, WASHINGTON.

WRENCH.

1,241,223.

Specification of Letters Patent. Patented Sept. 25, 1917.

Application filed December 4, 1916. Serial No. 134,972.

To all whom it may concern:

Be it known that I, JOSEPH KNOWLES, a citizen of the United States, residing at Edmonds, in the county of Snohomish and 5 State of Washington have invented certain new and useful Improvements in Wrenches, of which the following is a specification.

This invention relates to improvements in wrenches, more particularly to the class of 10 pipe wrenches, and has for one of its objects to improve the construction and increase the efficiency and utility of a device of this character.

Another object of the invention is to provide a device of this character in which the outer jaw is rendered slightly yieldable to increase the efficiency when strain is applied.

With these and other objects in view, the invention consists in certain novel features 20 of construction, as hereinafter shown and described and then specifically pointed out in the claims; and in the drawings illustrative of the preferred embodiment of the invention—

25 Figure 1 is a side elevation of the improved implement.

Fig. 2 is a transverse section on the line 2—2 of Fig. 1.

Fig. 3 is an elevation viewed from the 30 side opposite to the jaws.

Fig. 4 is an elevation viewed from the jaw side.

Fig. 5 is a perspective view of the recessed or socketed end of the stock.

35 Fig. 6 is a detached perspective view from beneath of the outer jaw.

Fig. 7 is a detached perspective view of the movable jaw from beneath.

Figs. 8 and 9 are views similar to Figs. 40 6 and 7 illustrating a modification in the construction.

Corresponding and like parts are referred to in the following description and indicated in all the views of the drawings by 45 the same reference characters.

The improved device comprises a stock or body portion 10 extended at one end into a hand grip. The stock is preferably flat or oblong transversely and with screw threads 50 12 in the opposite edges. At the end opposite to the hand grip the stock is enlarged laterally to provide a longitudinally directed recess or socket 13 with the sides 14 of the socket extending in parallel relation. The socket opens outwardly and later-

ally of the stock and is pierced to receive a holding bolt or pin 15. The outer jaw member is represented at 16 and reduced as shown at 17 to enter the socket 13. The reduced portion 17 is pierced to receive the 60 bolt or pin 15 whereby the jaw member 16 is swingingly coupled to the stock. The jaw member 16 is formed with an overhanging portion having pipe or rod gripping teeth 18. Bearing over the side portions 14 which define the recess or socket 13 is a relatively heavy member 19 of resilient material, preferably spring steel, and secured by a pin 20 to the reduced portion 70 17 of the outer jaw. The member 19 corresponds in width to the combined socket 75 13 and its side members 14, and operates to support the outer jaw slightly yieldable relative to the stock. The adjacent outer faces of the portions 14 of the stock at the 80 sides of the socket 13 and the outer face of the portion 17 of the outer jaw are flush, or in alignment transversely of the stock, when the outer jaw is in normal position, as shown in Fig. 1, so that the resilient member 19 85 lies flatly against the three portions and extends at its inner end beyond the inner end of the socket. The member 19 thus serves not only as a yieldable means for holding the movable jaw in position but also as a 90 clamping member to assist in coupling the movable jaw and the stock. The pivot 15 being located at some distance from the inner end of the portion 17 of the outer jaw, insures the full force of the resilient 95 member being exerted to retain the outer jaw yieldably in normal or initial position.

The member 19 also serves as a housing to effectually cover and protect the joint between the parts 14 and 17 and prevent the entrance of dust or other foreign matter which would injure the parts and cause abrasion between them. Slidably disposed relative to the stock is a movable jaw including a laterally enlarged head portion 21 and a depending portion 22. The jaw portion 21 is provided with pipe or rod engaging teeth 23, which coat with the teeth 18 of the jaw 16. Formed upon or attached to the portion 22 of the movable jaw are arms 24 105 which project beyond the portion 22 and encompass the threaded portion of the stock 10. The arms 24 are preferably integral with the portion 22 of the movable jaw, and couple the latter in slidable relation to the 110

The arms 24 are preferably integral with the portion 22 of the movable jaw, and couple the latter in slidable relation to the 110

stock 10. The adjacent faces of the stock 10 and the movable jaw are provided with a coacting slot and lip.

In Figs. 6 and 7 the lip 26 is shown projecting from the portion 17 of the outer jaw and the slot 27 formed in the movable jaw, while in Figs. 8 and 9 these portions are reversed with the lip on the movable jaw and the slot in the outer jaw. Either arrangement may be employed, as may be preferred.

Mounted for rotation upon the threaded portion of the stock is an operating nut 28, preferably cylindrical externally and provided with a roughened outer face to enable the operator to grip the nut more firmly. Formed in the nut 28 near one end is an annular channel 29, and extending from the portion 22 of the movable jaw or fingers are arms 30 adapted to engage in the channel 29. By this arrangement it will be obvious that when the nut is rotated upon the stock the movable jaw will be correspondingly actuated and adjusted nearer to or farther from the outer jaw, while the coacting lip 26 and slot 27 retain the movable jaw in position from lateral movement. At the same time the encompassing arms 24 retain the movable jaw in position relative to the stock and prevent the displacement therefrom without interfering with the movement of the jaw longitudinally of the stock.

Having thus described the invention, what is claimed as new is—

1. In a wrench, a stock having an outwardly opening socket, an outer jaw including a head and a reduced portion with the reduced portion engaging in said socket, a pivot uniting the socket portion of the stock

and the reduced portion of the outer jaw, a resilient member attached to the reduced portion of the outer jaw and corresponding in width to the stock and extending over the reduced portion of the outer jaw and partly over the head of the same and forming a housing to protect the joint between the stock and outer jaw, said resilient member operating to yieldably maintain the outer jaw with its socket engaging portion normally in alinement with the stock, an inner jaw, means for adjusting said inner jaw longitudinally of the stock, and a stud and guide channel carried by said outer and inner jaws and coacting to prevent lateral displacement of the inner jaw.

2. In a wrench the combination of a stock having an outwardly opening socket, an outer jaw including a head and a reduced portion engaging in said socket and provided with an outwardly directed stud, a pivot extending through the socket portion of the stock and the reduced portion of the outer jaw, a resilient member attached to the reduced portion of the outer jaw and corresponding in width to the stock and extending over the reduced portion of the outer jaw and partly over the head of the same and forming a housing to protect the joint between the stock and the outer jaw, said resilient member operating to yieldably maintain the outer jaw with its socket engaging portion normally in alinement with the stock, an inner jaw having a longitudinally directed channel to receive said stud, and means for adjusting said inner jaw longitudinally of the stock.

In testimony whereof I affix my signature,

JOSEPH KNOWLES. [L. S.]
